Patented Sept. 5, 1922.

INVENTOR.
Charles E. Rogers
BY Joseph A. Miller
ATTORNEYS.

UNITED STATES PATENT OFFICE.

CHARLES E. ROGERS, OF NEW LONDON, CONNECTICUT.

YARN REEL.

Application filed October 11, 1921. Serial No. 507,072.

To all whom it may concern:

Be it known that I, CHARLES E. ROGERS, a citizen of the United States, residing at New London, in the county of New London 5 and State of Connecticut, have invented new and useful Improvements in Yarn Reels, of which the following is a specification.

This invention relates to certain new and useful improvements in yarn reels, and the 10 primary object thereof is to provide a reel which maintains the hank or skein of yarn under tension so as to thereby take up all slack in the hank or skein, during unwinding of the yarn from the reel, thereby preventing overrunning of the hank or skein.

A further object of the invention is to provide spring means for effecting the tension on the yarn and to provide a simple and economical structure which can be easily 20 and quickly operated to place the hank or skein under tension.

Still further the invention aims to provide a novel structure for the purpose stated which involves a minimum of parts so as to 25 reduce cost of production and also likelihood of derangement of the parts.

Other and further objects will be later set forth and manifested in the course of the following description.

30 In the drawings:

Figure 1 is a side elevation of the invention;

Figure 2 is a section on line 2—2 of Figure 1; and

35 Figure 3 is a section on line 3—3 of Figure 2.

In proceeding in accordance with the present invention, a shaft S is employed upon which disks 1 and 2 are mounted, disk 1 40 being rigidly secured to the shaft, while disk 2 is rotatable on the shaft. The disk 1 carries a series of radial outwardly extending arms 3, while the outer ends of the arms have transverse bolts 4 attached thereto. 45 The disk 2 has a corresponding series of arms 5 pivoted at their inner ends thereto at 5' while the outer ends of these arms 5 have the yarn spools 6 secured thereto.

For the purpose of maintaining the disk 50 2 under constant tension, a coil spring 7 is employed having its inner end secured in fixed relation to the disk 1 and shaft S, while its outer end is secured to a bolt 8, the latter being adjustably secured in a curved 55 slot 9 formed in the disk 2, so as to allow

of regulation of the tension of the spring as desired.

A pivoted spring tensioned latch 10 is mounted on the hub 2' of the disk 2 and has its effective end formed to contact a stop 60 11 carried by the disk 1.

The bolts 4 extend through and operate in slots 5" formed in the arms 5 so that upon relative rotation of the disks 1 and 2, the arms 5 and therewith the spools 6 will 65 be moved from the position shown in dotted lines to the full line position of Figure 1.

The operation is as follows:

The operator first depresses the outer end of the latch 10 releasing the effective end 70 thereof from the stop 11 and then effects relative rotation of the two disks 1 and 2 so as to wind up the spring 7 and thus increase the tension thereof, at the same time causing the bolts 4 to move through the slots 5" 75 so that the parts are moved from the dotted to the full line position of Figure 1. The latch is then released causing the effective end thereof to again contact with the stop 11 holding the reel in the contracted or full 80 line position of Figure 1. The hank or skein of yarn is now placed on the reel, and the latch again depressed to disengage same from the stop 11, which allows the spring 7 to exert its action or tension on the disks 85 causing the latter to have a tendency to move the arms 5 and therewith the spools 6 outwardly or from the full to the dotted line position of Figure 1. In this manner, the skein or hank of yarn is maintained under 90 constant and uniform tension, so that all slack is taken up and overrunning of the hank or skein is prevented.

Having thus described my invention, what I claim as new and desire to secure by Letters Patent is:—

1. In a yarn reel, a shaft, a disk fixed on the shaft and having radial arms, bolts carried by the arms, a disk rotatable on the shaft, arms pivoted at their inner ends to 100 the rotatable disk and having spools on their outer ends and having slots receiving the respective bolts, a coil spring between the disks secured at one end to the fixed disk and adjustably secured at its opposite end 105 to the rotatable disk, a stop on the fixed disk, and a latch carried by the rotatable disk and engaging the stop.

2. In a yarn reel, a pair of relatively rotatable disks, a spring for normally ten- 110

2
sioning the disks to effect relative rotation thereof, spool carrying members pivotally carried by one disk, and means to cause the spool carrying members to move about their pivots to move outwardly from the last named disk through the tension of the spring.

3. In a yarn reel, a pair of relatively rotatable members, means to tension the members to effect relative rotation therebetween, spool carrying members swingingly carried by one member and means to swing the spool carrying members outwardly from the last named member upon relative rotation of the pair of members.

4. In a yarn reel, a fixed member, a rotatable member having a slot, spring means to tension the rotatable member, yarn engaging means carried by the rotatable, means to effect inward and outward movement of said yarn engaging means upon movement of the rotatable member, a stop on the in-

ner face of the fixed member, and a spring tensioned latch pivoted to the rotatable member and extending through the slot 25 thereof to engage opposite sides of the stop.

5. In a yarn reel, a relatively fixed disk having radial fixed arms, a relatively rotatable disk, slotted arms pivoted at their inner ends to the rotatable disk and having 30 yarn engaging means on their outer ends, spring means for tensioning the rotatable disk, projections carried by the fixed arms and operating in the slots of the pivoted arms, and means to releasably hold the rotatable disk under the tension of the said spring means.

In testimony whereof I have signed my name to this specification in the presence of two subscribing witnesses.

CHARLES E. ROGERS.
